(57) **CLAIM**

The ornamental design for a seed pod, as shown and described.

DESCRIPTION

FIG. 1 is a perspective view of a seed pod showing our new design;

FIG. 2 is another perspective view thereof;

FIG. 3 is a front view thereof, the rear view, right side view and left side view being a mirror image;

FIG. 4 is a top view thereof;

FIG. 5 is a bottom view thereof;

FIG. 6 is a cross-sectional view taken along lines 6-6 of FIG. 3 thereof;

FIG. 7 is a perspective view of another embodiment thereof;

FIG. 8 is another perspective view thereof;

FIG. 9 is a front view thereof, the rear view, right side view and left side view being a mirror image;

FIG. 10 is a top view thereof;

FIG. 11 is a bottom view thereof;

FIG. 12 is a cross-sectional view taken along lines 12-12 of FIG. 9 thereof;

FIG. 13 is a perspective view of another embodiment thereof;

FIG. 14 is another perspective view thereof;

FIG. 15 is a front view thereof, the rear view, right side view and left side view being a mirror image;

FIG. 16 is a top view thereof;

FIG. 17 is a bottom view thereof; and,

FIG. 18 is a cross-sectional view taken along lines 18-18 of FIG. 15 thereof.

(Continued)

The broken lines depict portions of the seed pod which form no part of the claimed design.

1 Claim, 9 Drawing Sheets
